HEATING OF DIES BY INTERNAL COMBUSTION

Alfred F. Bauer, Toledo, Ohio, assignor to National Lead Company, New York, N.Y., a corporation of New Jersey

Application May 9, 1957, Serial No. 658,208

2 Claims. (Cl. 22—74)

This invention relates to a method of heating die casting dies. More specifically it relates to a method of heating die casting dies in which the heat is applied to the interior of the die blocks by means of combustion of gas and air.

In the production of castings by the pressure die casting method, molten metal is introduced into the cavity at a high speed and under high pressure. Preheating of the dies, therefore, is necessary to prevent cracking of the die blocks when molten metal is shot into the die and to bring the temperature of the die blocks close to the operating range.

The customary method of preheating die casting dies is to direct a torch flame to the face of the die casting die mainly along the parting line of the die. This is a very inefficient and unsatisfactory method of heating because only a small portion of the B.t.u.'s of the combustion gases is transferred into the die while most of the heat escapes into the air. In directing the open flame of the torch towards the cavity areas, salient points of the cavity, especially thin cores and pins may overheat and anneal while the main die blocks are hardly warming up. Even though these shortcomings are well known the open torch method of heating dies has been the accepted heating method.

On large dies the deficiencies of this open torch heating method become much more pronounced. Heat transferred into large die blocks by open torches dissipates into the air almost as fast as if it can be absorbed by the blocks and, therefore, increases tremendously the heating time of the dies. With extremely large dies the open torch method never will bring the die steel up to the proper preheating temperature. In addition, the danger of overheating salient points and thin sections of the die cavity and the problem of oxidation and corrosion of the die steel by subjecting these areas to the open and corrosive flame of the torch over a lengthy period has an adverse effect on the lifetime of the dies.

When the die blocks of large dies take on the weight of several tons, the open torch heating method, therefore, becomes absolutely unsatisfactory. Therefore, a new heating method had to be found which is more effective and protects the steel more than the method with an open torch.

By employing an internal combustion system as herein described, through drilled or cast-in channels in the die blocks a much more efficient heating system has been developed. The heat of the combustion gases is penetrating into the die blocks through long channels and cannot escape into the air resulting in an extremely efficient heat exchange and in a relatively fast heating up of the largest die blocks.

Through additional holes along the passage way of the combustion gases secondary air can be injected (or sucked in) to create a soft flame and to lengthen the combustion area of a reduced gas mixture. This will guarantee uniform combustion and internal heating over any area of the die. Since the combustion gases are contained within

the internal channels of the die blocks, the gases do not come in contact with the die cavity and, therefore, do not create overheating and annealing of the steel nor an oxidation of the steel in the cavity.

5 The internal heating system of this invention can be applied to the die blocks during the starting period in order to preheat the die, but also during the operating cycle to heat outer sections of the die block. On large dies the inner sections which come in direct contact with 10 the molten metal have to be water cooled to prevent overheating while the heat passing through the steel does not flow fast enough to give the outer sections of the die the desired operating temperature.

In these cases of extremely large dies where the outer 15 sections of the die have to be heated during the die casting cycle, the invention offers ideal conditions in that the heat can be applied continuously or intermittently during the die casting cycle while at the same time other and predominantly inner sections of the die are heavily water cooled; thus creating ideal temperature control conditions within large dies.

With thermocouples built in large die blocks the internal 20 combustion system in conjunction with the water cooling of the dies lends itself to a very efficient and practical method of temperature control of die blocks especially on large dies.

It is, therefore, an object of this invention to provide means for efficiently heating large die blocks to the proper preheating temperature.

30 Another object of this invention is to provide a means for heating large die blocks which is not accompanied by the usual problems of overheating salient points and thin sections of the cavity and oxidation and corrosion of the die steel.

35 A further object of this invention is to provide means for heating die casting dies from the interior of the die blocks outwardly by the combustion of gas and air.

Another object of this invention is to provide means 40 by which sections of large dies more remote from the gate area may be heated through local heating channels while other sections of the die are being cooled under operating conditions.

Yet another object of this invention is to provide means 45 by which heat may be applied to the die blocks during the casting cycle.

These and other objects of the present invention will become apparent from the following more complete description and the drawings in which:

50 Figure 1 is a face view, partially sectioned, of a typical holding block for one die half, and

Figure 2 is a similar view of a second embodiment of the present invention.

Figure 1 shows impression block cavity 20 in the die holding block 10. The specific embodiment of the invention illustrated has two combustion chambers 11 and 11a extending laterally through said holding block from side 14 to the opposite side 15. The heating source is burner 30 which burns a mixture of a combustible gas and a combustion supporting gas which, because of the economics involved, will usually be natural gas and air and are available from a source of supply by means of supply lines 41 and 42 through control valves 43 and 44 into mixing chamber 40. The premixed gas from said mixing chamber is supplied through fuel line 35, which 55 may or may not have shut-off valves for the separate burners, to burner 30 which includes torch 31 provided with air ports 33, aspirator shell 32 and fuel tube 34. In the form of the invention illustrated in Fig. 1, flame 16 60 may, by proper adjustment of the length of said fuel tube and the relative amounts of combustible gas and air, be made to burn the full length of combustion chamber 65 70

11 beginning at entrance port 12 and continuing through the die block to exit port 13.

The burners are held in place adjacent to the entrance ports of said combustion chambers by means of burner supports or other suitable means in such a way that when the die halves are opened to permit removal of the casting, the burner assembly is moved and is held in the same position relative to the combustion chamber of the die block to which it is attached.

Prior to starting the operation of the die casting machine, during the "warm-up" period, the burners are turned on and the premixed gas and air mixture is ignited. In the apparatus of Fig. 1, the total quantity of air needed for complete combustion of the gas is not pre-mixed. A portion of the necessary air is introduced into the combustion chamber through aspirator shell 32 and air ports 33 of burner 30 by the aspirator action of the gas stream being fed into the combustion chamber. Additional air is drawn into the combustion chamber through the space between the burner and entrance port 12. By proper adjustment of gas valve 43 and air valve 44, a flame is produced which will extend the full length of the combustion chamber.

A modified form of combustion chamber 11b is shown in Fig. 2 employing only one torch 30. In this modification, the combustion chamber is cast into the die block by means of a pipe or tube and a portion or all of the chamber may follow the irregular path shown at 22 so as to apply heat more directly to desired portions of the die block.

Flame from torch 30 enters the combustion chamber at entrance port 12a and passes through the chamber to exit port 13a. Additional air to support combustion may be drawn in through air inlets 50 by the aspirator action of the gases and flame passing through the combustion chamber. By proper adjustment of the gas and air, it is possible to maintain a soft flame the full length of the combustion chamber.

By casting the combustion chamber in the die block, it can be given any desired configuration so as to apply more heat where desired and to avoid coolant lines, dowels and fastening bolts.

It is understood that the combustion chambers shown are for illustrative purpose only and are susceptible to considerable modification according to the specific needs of the application. Therefore, the form of the invention described is not intended to limit the scope of the following claims.

I claim:

1. A die casting die assembly including a holding block of substantially solid ferrous metal having a recess in one face thereof for holding an impression block in intimate contact therewith, said holding block containing at least

one combustion channel extending laterally through said holding block with its entrance and exit ports in opposite side faces of said block and at least one passage extending from an end face thereof and intersecting said combustion channel, the angle formed at the intersection of said passage and said combustion channel being such that air will be drawn in through said passage by the aspiratory action of gases passing through the combustion channel; a gas burner positioned on the side face of said

5 holding block adjacent the entrance port of said channel; sources of combustible gas and air, respectively, connected to said burner; said burner including a mixing chamber wherein said gas and air are intermixed prior to combustion; and means for igniting said gas mixture; said gas 10 and air sources having control means whereby each may be adjusted such that the flame produced by combustion of the gas mixture is contained generally within the confines of said combustion channel.

2. A die casting die assembly including a holding block 15 of substantially solid ferrous metal having a recess in one face thereof for holding an impression block in intimate contact therewith, said holding block containing a combustion channel generally encircling said recess in the holding block with its entrance and exit ports in one side 20 face of said block and at least one passage extending from an end face thereof and intersecting said combustion channel, the angle formed at the intersection of said passage and said combustion channel being such that air will be drawn in through said passage by the aspiratory action 25 of gases passing through the combustion channel; a gas burner positioned on the side face of said holding block adjacent the entrance port to said channel; sources of combustible gas and air, respectively, connected to said burner; said burner including a mixing chamber wherein 30 said gas and air are intermixed prior to combustion; and means for igniting said gas mixture; said gas and air sources having control means whereby each may be adjusted such that the flame produced by combustion of the gas mixture is contained generally within the confines 35 of said combustion channel.
